CLAIM

The ornamental design for a gameboard as shown and described.

DESCRIPTION

1. Gameboard

Fig. 1.1 is a front view of a gameboard in accordance with the present design;

Fig. 1.2 is a rear view thereof;

Fig. 1.3 is a top view thereof;

Fig. 1.4 is a bottom view thereof;

Fig. 1.5 is a left side view thereof; and

Fig. 1.6 is a right side view thereof.

This design is composed of two different square mesh patterns printed on front and back sides of one plain gameboard; each of the mesh patterns is edged by its own border lines as shown.

(Continued)

The broken lines depict unclaimed portions of the game-board, included for illustrative purposes only.
